UNITED STATES PATENT OFFICE.

GEORGE H. TAYLOR, OF NEW YORK, N. Y., ASSIGNOR TO THE KURSHEEDT MANUFACTURING COMPANY, OF SAME PLACE.

DESIGN FOR TRIMMING.

SPECIFICATION forming part of Design No. 27,845, dated November 9, 1897.

Application filed May 29, 1897. Serial No. 638,814. Term of patent 7 years.

To all whom it may concern:

Be it known that I, GEORGE H. TAYLOR, a citizen of the United States, and a resident of the city, county, and State of New York, have invented and produced a new and original Design for Trimming, of which the following is a specification.

The essential feature of my design is a trimming substantially as shown.

10 In the drawing, *a* is a band from which rises rouching or trimming, which rouching or trimming viewed laterally, as in Fig. 1, presents the appearance of a series of puffs or festoons *B*, which are fluted sinuously, the flutes running in a sinuous line from the base of the

festoon to near the top thereof, where a flute extends laterally of the sinuous line upward in a comparatively straight line, and in Fig. 2, when viewed in plan, presents the appearance of a sinuous fluted structure capped 20 with a sinuously-fluted band *b*, the said band forming the upper edge of the trimming.

What I claim is—

The design for trimming, substantially as shown.

GEORGE H. TAYLOR.
